UNITED STATES PATENT OFFICE.

MAURICE MORTDECAI GLASSER, OF CHARLESTON, SOUTH CAROLINA.

CEILING FAN.

1,409,090.

Specification of Letters Patent.

Patented Mar. 7, 1922.

Application filed September 28, 1920. Serial No. 413,307.

To all whom it may concern:

Be it known that I, MAURICE M. GLASSER, a citizen of the United States, and a resident of Charleston, in the county of Charleston and State of South Carolina, have invented certain new and useful Improvements in Ceiling Fans, of which the following is a specification.

My invention is an improvement in ceiling fans, and has for its object to provide a fan of the character specified, wherein the blades in addition to their rotary movement have a vertically swinging or oscillating movement imparted to them during their rotation, and controlled by their rotation, for distributing the current of air thrown by the blades over a larger area.

In the drawings:

Figure 1 is a side view of the improved fan,

Figure 2 is a section on the line 2—2 of Figure 1,

Figure 3 is a vertical section through the sleeve showing the reversing mechanism,

Figure 4 is a side view of another embodiment of the invention.

In the present embodiment of the invention shown in Figures 1 to 3 the improved fan comprises a suitable motor, as for instance an electrical motor which is arranged within a cylindrical casing 1. The said motor and casing are mounted to rotate on a shaft 2 which has a base 3 adapted to be secured to a ceiling, so that the motor and casing depend vertically at the lower end of the shaft. The shaft 2 is hollow, and the lead wires for the electrical current may pass through the shaft to the motor.

In the present instance the fan has four blades 4, extending radially from the motor casing, and each blade is pivoted to the casing to swing on a horizontal axis. At the inner end of each blade there is secured a plate 5, having a pair of hinged lugs 6 at its inner end which fit on opposite sides of a lug 7 extending radially of a casing 1. The lugs 6 are pivotally connected to the lugs 7, and means is provided for simultaneously swinging all of the blades vertically. The said means includes a sleeve 8 which is mounted to rotate on the shaft 2, and to reciprocate longitudinally thereof, and this sleeve has a pair of radially extending ears 9 at each blade. An arc shaped link 10 connects each pair of ears with the adjacent blade, the link

being pivoted to the ears at one end, and to a loop 11 on the plate 5 at the other.

Mechanism is provided for moving the sleeve 8 vertically of the shaft, the said mechanism being in the form of right and left hand screw threads on the shaft, which are adapted to be engaged by nut sections 15 and 16. These nut sections are connected to the arms of a yoke 17 which is pivoted at 18 within the sleeve, and at each end of the body of the yoke there is provided an extension 19 having a recess in its end, into which is threaded a pin 20. These pins 20 are adapted to engage the collars 12 at the end of the travel of the sleeve in each direction to shift the yoke.

As indicated in Fig. 3, the sleeve 8 is moving downwardly and the pin 20 is just about to come in contact with the bottom collar 12. Now when the lower arm 19 carrying pin 20 begins pressing against the bottom collar the dog 21 is permitted to swing the yoke 17 and cause the lower nut 16 to engage lower threaded portion of shaft 2 and at same time rocking the upper nut 15 out of engagement with the upper threaded portion of said shaft; the sleeve will commence to move slowly upward until the upper pin 20 begins to contact with the upper collar 12, when the reverse operation takes place. Thus the movement of the sleeve will be reversed and this will occur whenever a pin 20 engages a collar 12. The pins may be adjusted, by turning them into or out of the recesses, to insure that the reversal will take place at the proper time.

Means is also provided for releasably holding the yoke in adjusted position. The said means is in the form of a catch pin 21, which is mounted to slide in a radial recess in a collar 22 connected to the sleeve as indicated at 23. This collar encircles the shaft loosely and moves with the sleeve. The head of the pin is triangular as shown, and engages a beveled catch lug 24 at the center of the yoke body. A coil spring 25 encircles the pin between the head and the bottom of the recess, and normally acts to press the pin outwardly. When the yoke is swung, the catch lug 24 will force the pin inwardly and it will pass the head of the pin. As soon as the lug has passed the head of the pin, the spring will force the pin outwardly.

The fan shown in Figure 1 has the rotatable member of the motor outside, and

there is no difficulty in attaching the hinged lugs 7 to the rotating member. This is the Westinghouse type of fan, but in the Emerson type and the General Electric type, the 5 rotating element is also almost totally enclosed, and the blades must be fastened at the bottom. This type of fan as shown in Figure 4 comprises a shaft 26 having the base 27 for connection with the ceiling and carrying at 10 its lower end the motor casing 28. The rotating member of the motor is arranged within the casing, and the blades 29 are connected with the rotating element by means of the curved links 30 and the hinge plates 15 31, the latter being secured to the blades while the links are hinged to the hinge plates at their outer ends and rigidly connected to the rotatable member at their inner ends.

20 The links 32 which connect the sleeve 33 with the blades are pivoted at one end to the sleeve, and at the other to the hinge plates. The sleeve is of the same construction as the sleeve 8, having the reversing 25 mechanism for engaging the upper collar 12. It will be understood that the manner of attaching may be in accordance with the type of fan, the invention consisting in providing means for swinging the blades vertically 30 during their rotation.

The operation of the improved fan is as follows: When the fan rotates, the sleeve will reciprocate on the shaft 2, and the fan blades will be swung as indicated in dotted 35 lines in Figure 1.

With the usual type of fan fixed blades, the blast of air is directed at a limited area of the floor, and impinges on this limited area continuously, never varying its travel. 40 With the improved fan however in moving from the extreme downward position indicated in Figure 1 to the extreme upward position, the blades will drive a blast continuously increasing in area. On their downward movement, the area will decrease; thus the direction of the blast delivered by each blade will be continuously changing, sweeping 45 radially outwardly and inwardly.

I claim:

50 1. In combination with a fan comprising a rotatable casing and blades extending radially from the casing, of a hinge connected between each blade and the casing for permitting the blades to swing transversely of the plane of their rotation, and means controlled by the rotation of the blades for swinging said blades, a shaft for supporting the casing and the blades, a sleeve mounted to rotate on the shaft and 55 to reciprocate longitudinally thereof, a connection between each blade and the sleeve for simultaneously swinging the blades as the sleeve moves longitudinally of the shaft, and

a connection between the sleeves and the shaft for moving said sleeve longitudinally thereof in opposite directions. 65

2. In combination with a fan comprising a rotatable casing and blades extending radially from the casing, of a hinge connected between each blade and the casing 70 for permitting the blades to swing transversely of the plane of their rotation, and means controlled by the rotation of the blades for swinging said blades.

3. In combination, a ceiling fan comprising a hub and blades extending radially therefrom, said blades being hinged to the hub to swing transversely of the plane in which they rotate, and means controlled by the rotation of the blades for simultaneously 80 swinging the blades.

4. In combination, a ceiling fan comprising a rotatable element a support for the said element with which it is rotatably connected, and blades extending radially therefrom, 85 said blades being hinged to the element to swing transversely of the plane in which they rotate, and means controlled by the rotation of the blades for simultaneously 90 swinging the blades, said means comprising a sleeve mounted to move longitudinally of the support for the fan, a plurality of means supported by the sleeve and engaging the fan support to constrain the sleeve to move longitudinally of the support and 95 in opposite directions, means for engaging one of said means and disengaging the other at each end of the travel of the sleeve, and a connection between the sleeve and the blades for swinging said blades as the sleeve 100 moves.

5. In combination, a ceiling fan comprising a rotatable element and blades extending radially therefrom and hinged to the element to swing transversely of the plane 105 in which they rotate, and means controlled by the rotation of the blades for swinging them.

6. A fan comprising rotatable blades capable of swinging movement, and means 110 operable by the rotation of the blades for swinging the blades transversely of the axis of rotation first in one direction and then the other, whereby the normal diffusion of the air currents produced by the blades during rotation is continuously increased or decreased in area. 115

7. An air agitating device, comprising means for creating a current of air of a predetermined cross sectional area, and alternately oppositely reciprocating means for continuously and alternately increasing and decreasing the cross sectional area of the created current. 120
